CLAIM

The ornamental design for a shoulder rest for a shooting rest, as shown and described.

DESCRIPTION

FIG. 1 is a front perspective view of a shoulder rest for a shooting rest.

FIG. 2 is a back perspective view of a shoulder rest for a shooting rest.

FIG. 3 is a front view of a shoulder rest for a shooting rest.

FIG. 4 is a back view of a shoulder rest for a shooting rest.

FIG. 5 is a side view of a shoulder rest for a shooting rest, the opposite side view of the shoulder rest for a shooting rest being a mirror image thereof.

FIG. 6 is a top view of a shoulder rest for a shooting rest; and,

FIG. 7 is a bottom view of a shoulder rest for a shooting rest. The portions shown in broken lines in the illustrate an environment and are not part of the claimed design.
